UNITED STATES PATENT OFFICE.

ROBERT J. STOKES, OF TRENTON, NEW JERSEY, ASSIGNOR TO THERMOID RUBBER COMPANY, OF TRENTON, NEW JERSEY, A CORPORATION OF NEW JERSEY.

DESIGN FOR A VEHICLE-TIRE.

53,693.

Specification for Design.

Patented Aug. 5, 1919.

Application filed April 11, 1919. Serial No. 289,480. Term of patent 14 years.

To all whom it may concern:

Be it known that I, ROBERT J. STOKES, a citizen of the United States, and a resident of Trenton, county of Mercer, State of New Jersey, have invented a certain new, original, and ornamental Design for a Vehicle-Tire, of which the following is a specification, reference being had to the accompanying drawing, forming part thereof, in which—

Figure 1, is a plan view of the vehicle tire forming the subject of my new, original, and ornamental design; and Fig. 2, is a longitudinal sectional view.

I claim:—

The ornamental design for a vehicle tire, substantially as shown.

In witness whereof I affix my signature.

ROBERT J. STOKES.
